UNITED STATES PATENT OFFICE.

EDWARD HAROLD DEAN, OF EALING, LONDON, ENGLAND.

FOLDING OR COLLAPSIBLE CHAIR.

Application filed April 5, 1928, Serial No. 267,555, and in Great Britain January 26, 1928.

Folding or collapsible chairs are known whereof the rear legs are pivoted to the front legs at the top of which the back is formed, whilst the seat is adapted to be tipped-up when not required. Folding chairs are also known with the seat pivoted between the front legs, with the rear legs pivoted to the front legs on an axis above the level of the seat and means for causing co-action between 5 said seat and rear legs so that when the former is tipped up the latter are folded towards the front legs and the chair assumes its flat or collapsed state. This co-action between the seat and the rear legs may be 10 brought about e. g. by the engagement in longitudinal slots in the rear legs of pins projecting outwardly from that part of the seat in rear of its pivotal axis, or by replacing said pins by apertured elements or the like through 15 which said rear legs pass, but in either event the tipping up of the seat involves the folding of the rear legs towards the front legs and, although such chairs, when not required for use, can be collapsed or folded and stored in 20 a very small space, they present the disadvantage that the seat cannot be tipped up whilst the legs remain in their open or extended positions. The object of the present invention is to obviate this disadvantage by 25 the provision of a chair which can be collapsed into the same space as those mentioned above and yet, the seat of which, when required, can be tipped-up, without collapsing the legs, e. g. to facilitate the movement of 30 people between rows of chairs and in front of those chairs already occupied, thus enabling rows of chairs to be placed closer together with consequent increase of seating capacity on a given floor space.

40 According to this invention the improved folding or collapsible chair comprises a pair of front legs, in one with which the back is formed, a seat pivoted between said front legs, a pair of rear legs pivoted to said front legs on an axis above the level of said seat and an intermediate member or a pair of intermediate members pivoted relatively to said front legs and adapted, on the one hand, to co-act with said rear legs so that when 45 said member or members are turned about their pivotal axis said rear legs will be folded from their open or extended to their closed or collapsed position, or vice versa, and, on the other hand, to serve as stops for the seat

when the latter has been lowered to its substantially horizontal position. 55

When such a chair is to be folded from its closed or collapsed position to its open or extended position, for use, the mere act of folding down the seat brings about extension or 60 outward movement of the rear legs as the seat, acting against the stop portions of the intermediate members, causes said members to turn about their pivotal axis, whilst their consequent coaction with the rear legs causes 65 opening or extension of the latter. When, however, the seat is tipped-up from its substantially horizontal position, the intermediate members are unaffected and the rear legs remain open or extended, but if the rear 70 legs are to be closed or collapsed, this may be done by movement of the intermediate members about their pivotal axis.

The intermediate members may, with convenience, be pivoted coaxially with the seat 75 by passing a rod through said three elements and through the front legs. If desired, the intermediate members may be connected with one another so as easily to be operable simultaneously, for instance, they 80 may be formed from a strip of metal bent to a flat U-form the central portion of which extends across the chair beneath the seat thereof, whilst the limbs extend rearwardly for the passage therethrough of the main pivot rod whilst in rear of said rod said limbs may 85 be formed with lugs extending towards one another and adapted to overlie the sides of the seat near the rear edge thereof to constitute stops, whilst other portions of said 90 limbs are adapted to coact with the rear legs, e. g. in either of the manners set forth above.

Alternatively, the intermediate members may be inter-connected in rear of their pivotal axis, and if desired provided with a 95 depending handle knuckle-jointed to their connecting member so that after the seat has been tipped-up said handle may be pulled forwardly and upwardly to rock said intermediate members about their pivotal axis 100 and bring about the desired coaction with the rear legs to close or collapse them towards the front legs.

By way of example two forms of folding chair in accordance with the present invention are illustrated by the accompanying drawings wherein Figure 1 is a side elevation of one form showing the legs in the open or 105

extended position. Figure 2 is a plan thereof and Figure 3 is a side elevation showing the legs in the closed or collapsed position, parts of Figures 1 and 2 being broken away 5 for the sake of clearness, whilst Figures 4, 5 and 6 are similar views respectively of a modified form of chair.

The chair shown in Figures 1, 2 and 3 has a pair of front legs *a a*, in one with which 10 is formed a back consisting of a pair of curved bars *b b*, and a pair of rear legs *c c* pivoted as at *d* to the front legs *a a*. A rod *e* is passed transversely through the front legs *a a* through tubular distance pieces *f f*, 15 through a pair of intermediate members *g g*, and through a tip-up seat *h*. The intermediate members *g g* are constituted by the limbs of a flat U-shaped element the central part of which is arched forwardly as at *i*, 20 Figure 2 and is bent to approximately semi-circular channel section. As shown in Figures 1 and 3 each member *g* is provided with an outwardly directed pin *j* which extends into a slot *k* formed in the adjacent rear leg *c*, 25 so that when the two members *g g* are rocked about the rod *e* by means of the central part *i* the rear legs *c c* are moved from the position shown in Figure 1 to that shown in Figure 3, or vice versa. The intermediate members 30 *g g* are formed with inwardly directed lugs such as *m m*, (Figure 2) adapted to overlie the lateral edges of the seat *h* in rear of the pivotal rod *e* and to serve as retaining stops therefor when in the substantially horizontal 35 position as shown in full lines in Figure 1. Owing to the fact that there is no direct connection between the seat *h* and the rear legs *c c* it is possible, when required to tip-up the seat *h*, as indicated in broken lines 40 in Figure 1, leaving the remainder of the chair in its open or extended position. When it is desired to collapse the chair this may be done by pulling upwards the central part *i* which connects the intermediate members 45 *g g*.

Figures 4, 5 and 6 show a modified form of chair in which the rear legs are constituted by a rod of iron *c¹* bent to substantially U shape. In this case the intermediate members *g g* are bent outwardly and obliquely, 50 as shown at *n n*, and formed as eyes through which the limbs of the rod *c¹* are threaded in order that the necessary coaction between the members *g g* and the rear legs may be 55 produced in a manner known for the purpose of causing the pivoted seat of a folding chair to coact with the rear legs thereof.

I claim:

1. An improved folding or collapsible 60 chair comprising a pair of front legs, a back formed in one with said front legs, a seat pivotally mounted between said front legs, a pair of rear legs pivoted to said front legs on an axis above the level of said seat, an intermediate member pivoted relatively to said 65

front legs, a sliding connection between said intermediate member and said rear legs, and a stop on said intermediate member adapted to engage said seat when the latter has been lowered to its substantially horizontal position. 70

2. An improved folding or collapsible chair comprising a pair of front legs, a back formed in one with said front legs, a seat pivotally mounted between said front legs, a 75 pair of rear legs, pivoted to said front legs on an axis above the level of said seat, an intermediate member pivoted to said front legs coaxially with said seat, a sliding connection between said intermediate member and said rear legs, and a stop on said intermediate member adapted to engage said seat when the latter has been lowered to its substantially horizontal position. 80

3. An improved folding or collapsible 85 chair comprising a pair of front legs, a back formed in one with said front legs, a seat pivotally mounted between said front legs, a pair of rear legs pivoted to said front legs on an axis above the level of said seat, intermediate members pivoted relatively to said front legs, said intermediate members being connected with one another and formed with inwardly directed lugs adapted to overlie the 90 sides of said seat near the rear edge thereof when said seat has been lowered to its substantially horizontal position, said intermediate members being formed also with means having a sliding connection with said rear legs, said seat being adapted to be raised without collapsing said chair. 95

4. An improved folding or collapsible 100 chair comprising a pair of front legs, a back formed in one with said front legs, a seat pivotally mounted between said front legs, a pair of rear legs pivoted to said front legs on an axis above the level of said seat, intermediate members pivoted to said front legs coaxially with said seat, said intermediate members being connected with one another 105 and formed with inwardly directed lugs adapted to overlie the sides of said seat near the rear edge thereof when said seat has been lowered to its substantially horizontal position, said intermediate members being formed also with means having a sliding connection with said rear legs, said seat being adapted for raising or lowering without collapsing said chair. 110

5. An improved folding or collapsible 115 chair comprising a pair of front legs, a back formed in one with said front legs, a seat pivotally mounted between said front legs, a pair of rear legs pivoted to said front legs on an axis above the level of said seat, intermediate members pivoted relatively to said front legs, said intermediate members being connected with one another and formed with inwardly directed lugs adapted to overlie the 120 sides of said seat near the rear edge thereof 125

when said seat has been lowered to its substantially horizontal position, said intermediate members being formed also with outwardly extending pins adapted to extend 5 into slots in said rear legs to provide a sliding connection between said intermediate members and rear legs.

6. In a folding chair of the class described a main frame including front legs and a back 10 rest portion coextensive therewith, a pair of

rear legs pivoted to said main frame and adapted to collapse thereinto, a seat pivoted to said main frame below the pivot of said rear legs and being unconnected to said rear legs, and a pair of intermediate members 15 adjustably contacting with said rear legs and pivoted on said seat pivot to brace said seat in open position.

EDWARD HAROLD DEAN.
